UNITED STATES PATENT OFFICE

148,236

DESIGN FOR AN ASH TRAY

Philip S. Harper, Chicago, Ill., assignor to Harper-Wyman Company, Chicago, Ill., a corporation of Illinois

Application April 1, 1946, Serial No. 128,151

Term of patent 14 years

(Cl. D85—2)

To all whom it may concern:

Be it known that I, Philip S. Harper, a citizen of the United States, residing at Chicago, in the county of Cook and State of Illinois, have invented a new, original, and ornamental Design for an Ash Tray, of which the following is a specification, reference being had to the accompanying drawing, forming part thereof.

Figure 1 is a top plan view of an ash tray embodying my new design;

Figure 2 is a side elevational view of the ash tray;

Figure 3 is a side elevational view of the ash tray at right angles to Figure 2; and

Figure 4 is a perspective view of the ash tray.

I claim:

The ornamental design for an ash tray, as shown.

PHILIP S. HARPER.
